CLAIM

The ornamental design for a topload washing appliance, as shown and described.

DESCRIPTION

FIG. 1 is a first top perspective view of the topload washing appliance of the present invention;

FIG. 2 is a second top perspective view of the topload washing appliance of the present invention;

FIG. 3 is a top plan view of the topload washing appliance of the present invention;

FIG. 4 is a bottom plan view of the topload washing appliance of the present invention;

FIG. 5 is a first side elevation view of the topload washing appliance of the present invention;

FIG. 6 is a second side elevation view of the topload washing appliance of the present invention;

FIG. 7 is a third side elevation view of the topload washing appliance of the present invention;

FIG. 8 is a fourth side elevation view of the topload washing appliance of the present invention; and,

FIG. 9 is another first side elevation view of the topload washing appliance of the present invention with the door in an open position to view the underside of the topload washing appliance door.

The broken lines in the figures are for contextual purposes or show the environment and form no part of the claimed design.

The stipple pattern in the figures indicates a transitional condition applied to the underside of the transparent material moving from the outer edge to the interior. The transition material is located between the transparent material and the lid base.
